(57) **CLAIM**

The ornamental design for a headset, as shown and described.

DESCRIPTION

FIG. 1 is a front view of a headset, showing my new design;
FIG. 2 is a top plan view thereof;
FIG. 3 is a bottom plan view thereof;
FIG. 4 is a rear plan view thereof;
FIG. 5 is a left plan view thereof;
FIG. 6 is a right plan view thereof; and,
FIG. 7 is a perspective view thereof.
